UNITED STATES PATENT OFFICE.

WILLIE G. EATON, OF NASHUA, NEW HAMPSHIRE, ASSIGNOR TO THE DRAPER COMPANY, OF PORTLAND, MAINE, AND HOPEDALE, MASSACHUSETTS.

WEFT-FORK MECHANISM FOR LOOMS.

SPECIFICATION forming part of Letters Patent No. 624,765, dated May 9, 1899.

Application filed January 19, 1899. Serial No. 702,619. (No model.)

To all whom it may concern:

Be it known that I, WILLIE G. EATON, of Nashua, county of Hillsborough, State of New Hampshire, have invented an Improvement in 5 Weft-Fork Mechanism for Looms, of which the following description, in connection with the accompanying drawings, is a specification, like letters and figures on the drawings representing like parts.

10 In United States Patent No. 529,943, dated November 27, 1894, a loom is shown provided with means for automatically inserting a fresh supply of filling into the shuttle upon breakage of the shuttle-filling thread, and devices 15 are also therein provided for stopping the loom should the filling fail to be laid in the shuttle after the transfer of a fresh supply of filling. The first or primary movement of the weft-fork slide in said patent is utilized to 20 put into position the filling-transferring mechanism after the absence of filling opposite the weft-fork, and if after the transfer has been effected the filling-thread of the fresh supply fails to be laid in the shed the weft-fork is not 25 tilted for the second time and the slide is given an additional or secondary movement sufficient to knock off or stop the loom.

My present invention relates to weft-fork mechanism having successive movements imposed thereto under the circumstances set forth above, but more particularly adapted for use with looms wherein more than two harnesses are employed, it being understood that in such cases if the fresh filling after 35 failure is not introduced into the proper shed a defect will be very apparent in the cloth, and this invention has for its object the production of means for obviating such defects.

I have so arranged the operation of the novel 40 mechanism to be hereinafter described that upon failure of the fresh filling to be laid in the proper shed the loom will be stopped.

While my invention is herein shown as adapted to coöperate with a four-harness 45 weave, it is not restricted thereto.

Figure 1 is a top or plan view of the end of the breast-beam of a loom adjacent the shipper-handle with weft-fork mechanism embodying my invention applied thereto. Fig. 2 is an en-

larged transverse sectional view thereof on the 50 line xx , looking toward the right, Fig. 1, four harness-frames being shown at the left-hand side of the figure, the parts being represented in the position assumed when the loom is running properly. Fig. 3 is a view similar to 55 Fig. 2, but showing the weft-fork slide in outward position due to its first or primary movement upon failure of the filling to tilt the weft-fork; and Fig. 4 shows the position of the parts on the secondary outward movement of 60 the weft-fork slide on the next pick but one to that on which the failure of the filling was first detected.

The breast-beam A, provided with the usual notched holding-plate A' for the shipper-handle S and having pivotally mounted upon it a knock-off lever K, has bolted to it a stand a, having a suitable guideway a', in which is adapted to reciprocate a slide b, upon which is pivoted at b' a weft-fork b³, the latter having a tail b⁴, Fig. 1, to be engaged by a hook b⁵, pivoted on the upper end of the weft-hammer A¹⁰, the hook sliding on a support b^x, (see dotted lines, Fig. 2,) carried by the slide b. A check c⁴, pivoted on the slide, aids in 75 turning the weft-fork on its pivot after it has been tilted, as in said patent referred to. At its outer end the slide b is provided with a projection b⁶, against which normally rests a lever-arm d^x, loosely mounted on the rock-shaft d', which controls the filling-transferring mechanism, as in said patent, said arm having a depending foot d¹⁰, adapted to engage, as usual, the actuating-pawl of the take-up mechanism, (not shown,) so that the take-up 80 will not be operated each time the slide b is moved outward. A latch f, having upturned ears f', is pivoted at f² on the slide b, said latch having on its under side a cam f³, Fig. 2, while a dog f^x is fulcrumed at f⁴ on 85 the ears, the outer end of said dog being laterally offset and extended forwardly, as at f⁵, at one side of an outwardly-extended tongue f⁶, forming part of the latch, as best shown in Fig. 1, the under surface of the offset portion being convexed, as at f⁷, Fig. 2. The weft-fork slide b is recessed longitudinally to receive a sliding controller d², (see dotted lines,

Figs. 2 and 3,) having on its upper side a cam-lump d^3 and oppositely-turned or enlarged at its ends, the upturned end d^4 being in the path of the weft-hammer, while its outer downturned end d^5 is adapted to at times engage a shoulder a^2 , Fig. 2, forming a part of the stand a , the opposite side of the shoulder forming a stop for the projection b^6 when the weft-fork slide is in normal inward position, 10 the normal position of the weft-fork mechanism being shown in Figs. 1 and 2 of the drawings. A second arm d^{12} , fast on the rock-shaft d' , is upturned and bent rearwardly at its upper end, as at d^{13} , below the path of movement 15 of the latch-tongue f^6 , while the latter is maintained elevated by the controller d^2 , as shown in Fig. 2, the end d^{13} being offset or bent laterally to clear the outer end of the slide b . (See Figs. 1 and 3.) When the controller 20 releases the latch, the end of the arm d^{12} will under certain conditions (to be described) be in the path of the tongue f^6 and will be moved by it on the outward movement of the weft-fork slide to rock the controlling rock-shaft 25 d' of the filling-transferring mechanism.

A detent h , longitudinally slotted at $h' h^2$ to receive the pivot f^2 and a stud 5 on the latch f , is bent laterally at its outer end at h^3 to extend under the convex portion f^7 of the 30 latch-dog and maintain it elevated, while its opposite end is oppositely bent at h^4 to extend across the outer side of the upturned end a^4 of the controller.

When the loom is running properly, the 35 weft-fork is tilted by engagement with the filling at each forward beat of the lay, and the weft-fork mechanism remains in the position shown. Should the filling fail, however, the fork will be tilted, its tail b^4 will be engaged by the hook b^5 , and the outward stroke of the weft-hammer will operate to move the slide b outward, giving it its primary movement to thereby swing the foot d^{10} by or through the arm d^8 and the slide projection 40 b^6 and stop the take-up on that pick. The detecting action of the weft-fork usually takes place at every alternate pick, and let it be supposed that four harnesses are used, with the filling-supplying mechanism at one side 45 of the lay, with the weft-fork at the other side, and that for convenience of description the filling fails as the shuttle is thrown toward the weft-fork. The primary movement of the weft-fork slide, hereinbefore referred 50 to, on the first pick prevents the operation of the take-up, and this same movement of the slide brings the end d^5 of the controller against the shoulder a^2 , and the controller is stopped, permitting the cam f^3 to drop off 55 from the cam d^3 , lowering the latch f , so that the tongue f^6 thereof will rest on the end d^{13} of the arm d^{12} ; but the detent h will still hold the dog f^5 above the end of the knock-off lever K , extended in front of said latch-dog, 60 such condition of the parts being shown in Fig. 3. After its outward movement the slide b returns to its normal position, the

latch-tongue f^6 dropping down behind the upper end d^{13} of the arm d^{12} , and on the second pick, a non-detecting one, the shuttle is 70 thrown across the lay away from the weft-fork, while on its return on the third and detecting pick the fork will not be tilted and the slide will be given its secondary outward movement, tilting the arm d^8 , as before; but 75 this time the engagement of the latch-tongue f^6 with the arm d^{12} will swing the latter also, (see Fig. 4,) rocking the shaft d' to put the filling-supplying mechanism into position to 80 transfer a fresh supply of filling to the shuttle at the next or fourth pick, the shuttle then having returned to the right-hand end of the lay. The outer bent end or ear h^3 of the detent h will wipe over a fixed stop h^8 (shown as a hook-like plate secured to the 85 outer end of the guide a') on the return of the slide b to normal position after its primary outward movement, and as the tongue f^6 drops off from the bent end of the arm d^{12} the end h^3 of the detent will drop behind the 90 shoulder 25 of the stop. On the secondary outward movement of the slide described the stop h^8 prevents continued outward movement of the detent, withdrawing it from the shoulder f^7 of the latch-dog just after the 95 point of the latter has passed beyond the inner edge of the knock-off lever K , so that the dog will travel over the latter, as shown in Fig. 4. The shuttle is supplied with fresh filling on the fourth pick, as stated, so that 100 if the shuttle threads properly the filling will be laid in the shed at the fifth pick, a detecting-pick, and corresponding to pick No. 1 of the 1, 2, 3, 4 cycle, so that the filling will be laid in that shed of the cycle 105 corresponding to the shed of the previous cycle in which it failed. Supposing the new filling-thread to be thus properly laid in the correct shed, the weft-fork will be tilted and the hook b^5 will not engage its tail; but the 110 upper end of the weft-hammer as it completes its outward stroke will engage the upturned end d^4 of the controller and push it into the position shown in Fig. 2, thereby 115 lifting the latch f into its normal position, it being understood that the slide b has returned to the position shown in Fig. 2 by the usual 120 spring, as s^8 , Fig. 1, but with the dog f^5 behind the knock-off lever K , it having dropped from the position shown in Fig. 4 on the inward movement of the slide following the assumption of such position. If, however, the new filling-thread should not be laid in the 125 shed, then the weft-fork will not be tilted and the hook b^5 will engage the tail of the fork, so that the slide b will be given a third outward movement as the weft-hammer moves toward the breast-beam and the dog will act against the inner side of the knock-off lever, 130 turning it to release the shipper-lever and stop the loom. When the detent is held by the stop h^8 , as described, its inner laterally-turned end h^4 will be brought into position 135 against the outer face of the upturned end d^4 .

of the controller d^2 , as shown in Fig. 4, so that when the filling is properly laid the action of the weft-hammer in returning the controller to normal position, and thereby lifting the latch 5 f , will also operate to return the detent to normal position to engage the shoulder f^6 of the latch-dog and return the latter to its normal position, thus resetting the parts ready to operate on a subsequent failure of the filling.

10 By the mechanism herein shown I am enabled to not only effect the transfer of fresh filling, so that the filling will be laid in the proper shed of the cycle, the various parts being automatically reset in normal position, 15 but to also effect the stoppage of the loom should the fresh filling fail to be properly laid in the required shed.

The mechanism is simple, effective, and not liable to get out of order, the several 20 parts performing their duties quickly and accurately without regard to the speed of the loom.

25 In Fig. 2 I have shown a part of the filling-supplying mechanism, designating the trans- ferrer as F' , (shown in dotted lines and mounted on the stud F ,) said mechanism operating to transfer a fresh supply of filling to the shuttle when it is in the shuttle-box of the lay adjacent to the filling-feeder F^X , substan- 30 tially as in United States Patent No. 529,940, dated November 27, 1894, to which reference may be had.

Having described my invention, what I claim as new, and desire to secure by Letters 35 Patent, is—

1. In a loom, filling-supplying mechanism, controlling means therefor operative by or through failure of the filling, retarding means to delay the operation of the filling-supply- 40 ing mechanism for a predetermined number of picks after filling failure, stopping means for the loom, and an actuator therefor operative upon failure of the fresh filling to be properly laid in the shed.

45 2. In a loom, filling-supplying mechanism, controlling means therefor operative by or through failure of the filling, retarding means to delay the operation of the filling-supply- 50 ing mechanism for a predetermined number of picks after filling failure, stopping means for the loom, an actuator therefor operative upon failure of the fresh filling to be properly laid in the shed, and means to prevent take- 55 up of the cloth while filling is absent from the shed.

3. In a loom having three or more harness members, filling-supplying mechanism, controlling means therefor operative by or through failure of the filling, retarding means 60 to delay the operation of the controlling means after detection of the filling failure, to effect the introduction of fresh filling into the shed of the cycle corresponding to that one in which failure was detected, stopping means 65 for the loom, and an actuator therefor operative upon failure of the fresh filling to be laid in its shed.

4. In a loom, filling-supplying mechanism, controlling means therefor operative by or through failure of the filling, retarding means 70 to delay the operation of the filling-supply- ing mechanism for a predetermined number of picks after filling failure, stopping means for the loom, and an actuator therefor opera- 75 tive upon failure of the fresh filling to be properly laid in the shed, combined with means to reset the parts and render said actuator inoperative if the fresh filling is prop- erly laid.

5. In a loom, a shipping-lever, a knock-off lever; and weft-fork mechanism, including a latch having a pivotally-connected actuator to coöperate with the knock-off lever, a latch- controller, and a detent for the actuator, primary operation of said mechanism due to absence of filling causing the controller to release the latch, a secondary movement acting to withdraw the detent from the actuator and permit the latter to drop onto the knock- off lever, and a third movement of said mech- 90 anism operating the actuator to move the knock-off lever and stop the loom.

6. In a loom, knock-off devices, and weft- fork mechanism, including a latch having a normally-inoperative actuator to coöperate 95 with the knock-off devices, a latch-controller, and a detent for said actuator, combined with means to operate a change of filling, primary operation of the weft-fork mechanism due to absence of filling releasing the latch, a sec- 100 ondary movement of said mechanism operat- ing said means by the latch and also with- drawing the detent from the actuator, a third movement of said mechanism, due to absence 105 of the fresh filling in the shed, moving said actuator into engagement with and to operate the knock-off devices to effect stoppage of the loom.

7. In a loom, a shipping-lever, a knock-off lever; means to operate a change of filling, 110 including a lever having a bent upper end, coöperating weft-fork mechanism, including a slide, a movable latch mounted on said slide and provided with a rigid tongue and a pivoted actuator, and a detent for the latter, 115 a latch-controller to release the latch on the primary movement of the slide and permit its tongue to fall on the bent end of said lever, secondary movement of the slide rocking said lever through the latch-tongue, and a stop to 120 engage said detent on such secondary move- ment of the slide, to thereby release the actuator and permit it to fall upon the knock- off lever, a third movement of the slide, after change of filling, and due to absence of fresh 125 filling in the shed, moving said knock-off lever by engagement with the actuator, to stop the loom.

8. In a loom, a knock-off lever; weft-fork mechanism, including a slide, an attached 130 latch, an actuating-dog to engage the knock- off lever, and a detent for said dog, both mounted on the latch, a latch-controller to normally maintain the dog and detent in co-

operation and the latch inoperative, and a stop to withdraw the detent from the dog, primary movement of the slide moving the controller to release the latch and position 5 the detent in the path of its stop, the secondary movement of the slide, operating through the stop to withdraw the detent from the dog, the latter moving thereby into position to operatively engage the knock-off lever upon a 10 third movement of the slide.

9. In a loom, a knock-off lever; weft-fork mechanism, including a slide, an attached latch, a dog to engage the knock-off lever, and a detent for said dog, both mounted on the 15 latch, a latch-controller movable longitudinally in the slide and bent at its inner end across the detent, a fixed shoulder to engage and stop the controller on the primary movement of the slide due to absence of the filling, 20 and thereby release the latch, and a stop adapted to withdraw the detent from the dog on the secondary movement of the slide, due to continued absence of filling, subsequent return of the controller into normal position re- 25 setting the latch and detent.

10. In a loom, a weft-fork mechanism, including a slide, a latch carried thereby having a rigid tongue, a latch-controller, to normally maintain the latch and tongue elevated,

a dog pivotally connected with the latch, and 30 a detent for said dog, mounted to slide on the latch, combined with means to operate a change of filling, including a member to first support the tongue and to thereafter be engaged and moved by it, and a knock-off lever, 35 primary movement of the slide, after detection of failure of filling, withdrawing the controller to release the latch and permit descent of the latch-tongue on said member, the detent maintaining the dog inoperative, second- 40 ary movement of the slide due to a second absence of filling bringing said latch-tongue into operative engagement with said member, to move the same, and also withdrawing the detent from and permitting the dog to fall upon 45 the knock-off lever, a third movement of the slide, following immediately the operation of the filling-changing means, effecting operative engagement of the dog and knock-off lever, to move the latter and thereby stop the 50 loom.

In testimony whereof I have signed my name to this specification in the presence of two subscribing witnesses.
